UNITED STATES PATENT OFFICE.

WALTER LINK, OF AJO, ARIZONA, ASSIGNOR TO AMERICAN AIRSHIP ASSOCIATION,
OF AJO, ARIZONA, A CORPORATION OF ARIZONA.

AIRSHIP.

Application filed September 19, 1921. Serial No. 501,774.

To all whom it may concern:

Be it known that I, WALTER LINK, a citizen of the United States, residing at Ajo, in the county of Pima and State of Arizona, have 5 invented a new and useful Improvement in Airships, of which the following is a specification.

This invention relates to improvements in airships of the lighter than air type, and 10 particularly to dirigibles.

The main object of the present invention is to decrease the head pressure or head on 15 resistance to movement of the airship, particularly against a headwind and to reduce the drag incidental to or arising from longitudinal pressures without resorting to extreme stream line construction and thus retaining the advantages of an approximately 20 cylindrical gas-containing body in regard to lifting power.

A further object of the invention is to stabilize the movement of the airship and to overcome or reduce the danger attendant upon landings made in strong winds.

25 The accompanying drawings illustrate embodiments of my invention, and referring thereto:

Fig. 1 is a side elevation of the body of an airship provided with my invention;

30 Fig. 2 is a rear elevation of same;

Fig. 3 is a vertical section taken on line 3—3 in Fig. 2;

35 Figs. 4, 5 and 6 are partially vertical sections showing modifications of the invention;

Fig. 7 is a transverse section on line 7—7 in Fig. 6.

Referring to Figs. 1 to 3, my invention is 40 therein shown as applied in connection with a dirigible or airship body 1, which may comprise the usual framework and envelope filled with a buoyant gas and may be provided with the usual means, not shown, for propulsion and for support of passengers, 45 etc. Said body 1 is, or may be, tapered at each end in the usual manner and the rear or stern portion of the body is enclosed or surrounded by a tubular member 2, which may be cylindrical in form and is somewhat 50 larger in diameter than the portion of the body 1 enclosed thereby, so as to leave a space 3 between said tubular member 2 and the rear portion of said body. The said tubular member 2 extends in part at least 55 around the main body or untapered por-

tion of the air ship, and is larger than said main body so that the space 3 aforesaid extends around said main body. Said tubular member 2 may be supported on the body 1 in any suitable manner, for example, by 60 fins or ribs 4, which extend radially from the body 1, and which preferably project somewhat beyond the tubular member 2, as shown in Figs. 1 to 3. Fins or ribs 5 may also extend rearwardly from the stern of the body 65 1 to form stabilizing fins. Four of the fins or ribs 4 are herein shown, but it will be understood that any desired number may be used; or, if desired, the tubular member 2 may be supported in any other suitable manner, the 70 mounting of said tubular member being, however, such as not to seriously interfere with the passage of air through the space 3. The forward end of said tubular member 2 may flare slightly, as indicated at 6 in Figs. 75 1 and 3. The stern portion 7 of the dirigible body 1 may be of any suitable shape, either gradually tapering in a curve to give a stream line effect, for example, as indicated in Fig. 3, or it may be conical, as shown in Fig. 4, or hemispherical, as shown in Fig. 5. The tubular member 2 may be forwardly tapered, as shown in Fig. 4, or rearwardly tapered, as shown in Fig. 5. The stabilizing fins 5 may be extended forward, as shown in 85 Fig. 5, to support the tubular member 2 on the body 1. If desired, the fins 5 may, as shown in Fig. 4, be carried by rearwardly extending bars 15.

The gas containing body is of approximately cylindrical construction throughout the greater portion of its length, so as to provide for great lifting power in proportion to the weight of said body, and the tubular member 2 surrounds the cylindrical 90 major diameter portion of the gas-containing body only at the rear end portion of said major diameter portion. In order to secure the advantages of this invention in diminishing head on resistance without at the same 100 time introducing excessive surface resistance, it is necessary that the tubular member should be relatively short as compared with the cylindrical gas-containing body, and in any case it should be less than one-half the 105 length of the gas-containing body. The extent to which the tubular member overlaps or surrounds the major diameter portion of the gas-containing body must be determined in any particular case by actual test, but in 110

order to secure effective action according to this invention the portion so surrounded must be a material portion or considerable fraction of the length of the major diameter portion of the gas-containing body, and in any case the amount of overlap of the tubular member and the major diameter portion of the gas-containing body should be at least one-tenth of such major diameter portion.

10. In the operation of the airship by the usual propelling means, the body 1 travels in the direction of the arrow and I have found in such operation that the effect of the tubular member 2 is to stabilize the 15 movement, tending to prevent sudden deviations or changes of course, and also tending to decrease the head on resistance or head pressure and to reduce the drag incidental to or arising from longitudinal pressures.

In some cases, it may be desirable to provide for adjustment of the tubular member 2 longitudinally on the body 1. For this purpose said tubular member may, as shown 25 in Figs. 6 and 7, be mounted to slide on longitudinal ways or guides 8 on the body 1, said member 2 being provided, for example, with slides 9, which run in said ways, and which may be connected at their rear ends to a 30 frame 10 to which is secured a rope or cable 11 whereby the tubular member 2 may be drawn forward. Another cable 12 is mounted on a pulley 13 and connected to the tubular member 2, so as to draw the same 35 rearwardly, the two cables 11 and 12 leading to any suitable part of the ship for operation or control of the same.

By shifting the tubular member 2 longitudinally in this manner a variation in the 40 stabilizing and head pressure decreasing action may be effected. It will be understood that the air space or distance between the hull or body of the airship and the enclosing tube will be determined in any particular case by suitable tests, so as to effect the 45 desired result with different shapes of the stern of the body.

What I claim is:

1. An aerial vehicle comprising a gas con-

taining body having a substantially cylindrical major diameter portion and a tubular member of less length and of larger diameter than said major diameter portion and surrounding both a substantial part of said major diameter portion and a substantial 55 part of the tapering rear end portion of the said gas containing body, said tubular member being open at both ends to permit free passage of air between the cylindrical body portion and the said tubular member. 60

2. A construction as set forth in claim 1, in which the said tubular member surrounds the major diameter portion of said gas-containing body for at least one-tenth the length of said major diameter portion. 65

3. An aerial vehicle of the lighter than air type comprising a gas-containing body, a tubular member surrounding said body and spaced therefrom to form a passage for air between the said body and said tubular member, and fins extending rearwardly from 70 said tubular member.

4. An aerial vehicle of the lighter than air type comprising a gas-containing body, a tubular member surrounding said body and spaced therefrom to form a passage for air between said body and said tubular member and fins extending outwardly from said 75 tubular member.

5. An aerial vehicle of the lighter than air type comprising a gas-containing body, a tubular member surrounding said body and spaced therefrom to form a passage for air between said body and said tubular member, and fins extending rearwardly and outwardly from the tubular member. 80

6. In a dirigible vehicle of the lighter than air type, the combination with the gas-containing body thereof of a tubular member surrounding a portion of said body and spaced therefrom to form a passage for air between said body and tubular member, and means for controlling the longitudinal position of said tubular member on said body. 85

In testimony whereof I have hereunto subscribed my name this 9th day of September, 1921.

WALTER LINK.
